DESIGN FOR AN ENVELOPE

George W. Hunter, Wayne Township, Cass
County, Mich.

Application February 15, 1939, Serial No. 83,011

Term of patent 7 years

To all whom it may concern:

Be it known that I, George W. Hunter, a citizen of the United States, residing in the township of Wayne, county of Cass, and State of Michigan, have invented a new, original, and ornamental Design for an Envelope, of which the following is a specification, reference being had to the accompanying drawing, forming a part thereof.

Fig. 1 is a perspective view of an envelope embodying my design. The design is characterized

by the colored opaque vertical margin portions, as shown.

Fig. 2 is a perspective view showing the back transparent panel of the container and showing in dotted lines the back side of the front panel.

The opaque portions of the design embody color contrasts.

I claim:

The ornamental design for an envelope, as shown and described.

GEORGE W. HUNTER.
